UNITED STATES PATENT OFFICE.

ROBERT WILHELM VOIGT, OF DRESDEN, GERMANY, ASSIGNOR TO THE FIRM JOHANN CARL MÜLLER, OF DRESDEN, GERMANY.

MACHINE FOR PACKETING CIGARETTES.

Application filed May 31, 1927, Serial No. 195,419, and in Germany June 4, 1926.

This invention relates to machines for assembling cigarettes or the like of the kind in which the cigarettes are first packed in a shell which is then inserted in a container.

5 In accordance with the present invention the transfer of the cigarettes from the feed band onto a common guide is effected by pushers of plungers which are secured to a chain or the like arranged over the feed 10 band and moved in the longitudinal direction of said chain. The cigarettes on the feed band are fed transversely of their longitudinal direction. A plurality of transverse feeding bands for the cigarettes are 15 arranged adjacent one another of which each feeds the cigarettes of one group, horizontal trough shaped guides being located between the separate feeding bands in stepped relation to one another, the different 20 levels thereof varying from one another by the amount of the thickness of a cigarette so that the cigarettes first engaged by a pusher are fed over the next group or layer of 25 cigarettes and then by lowering the pusher the two superposed layers of cigarettes are 30 moved forward to the next group and so on. The improved machine is moreover distinguished by the particular formation of the transverse feeding means and the means for exactly arranging the cigarette groups as is hereinafter more fully explained.

The invention is illustrated in the accompanying drawings in Fig. 1 in plan view and in Fig. 2 in horizontal longitudinal section on the line 2—2 of Fig. 1 looked at in the direction of the arrows. Fig. 3 is a vertical cross-section on the line 3—3 of Fig. 1 also looked at in the direction of the arrows. Fig. 3^a is a detail view to a larger 40 scale than Fig. 3 and shows the drum 4 with cigarettes gripped by rakes. Figs. 4 and 5 are detail views and show feelers in two different positions. Figs. 6 and 7 are also detail views and show a presser with actuating means, Fig. 7 being a vertical cross-section to a larger scale than Fig. 6 on the line 7—7 of Fig. 6 looked at in the direction of the arrow.

As shown in Fig. 1 three feed hoppers 1 are provided from which the cigarettes are fed in three parallel tracks to the transverse guide at the end of which is located the slide Z to which the cigarettes are to be fed.

55 As will be clearly seen more particularly

from Fig. 3, the bottom of each hopper 1 is formed by the upper flight of an endless belt 3 travelling in the direction of the arrow and led over the pulleys 2. Beyond the front pulley 2 a cylinder or drum 4 extends into 60 the hopper which drum is formed on its periphery with pockets 5 each adapted to receive a cigarette. Between the pulley 2 and the drum 4 is a bridge piece 6 serving for the transfer of the cigarettes to the drum. 65 The front pulley 2 is driven by the drum shaft 7 through gearing 8, 9, 10. This shaft 7 is itself driven by means of a worm and worm wheel from the cross shaft 11.

The cigarettes are thus fed to the pockets 70 5 of the drum 4 by the endless band 3. To regulate the supply and prevent jamming or piling of the cigarettes a shaking device is afforded by a stripper or distributor 14 secured to a rock lever 12 which is pivotally 75 mounted at 13 on the hopper 1, which stripper at its lower end extends among the cigarettes and maintains them in continuous motion and also determines the quantity of cigarettes which are allowed by it to pass to 80 the drum 4. To the lever 12 is connected a link 15 which is pivoted at the end of a double armed lever 16 which rocks about the pivot 17 and on the end of which is mounted a roller 18 or the like co-operating with a 85 cam disc 19, the cam portion of which repeatedly actuates the roller 18 and thereby sets the lever 16 in continuous vibration, a spring (not shown) serving to maintain the roller 18 continuously in engagement with 90 the cam disc 19.

The cigarettes pass into the separate pockets in the drum 4 which rotates in the direction of the arrow, a roller 20 arranged above the drum 4 serving as a stripper and 95 serving to return any excess quantity of cigarettes to the hopper 1. On the other side of the stripper roller 20 the cigarettes are delivered from the pockets 5 of the drum 4 to a passage, the cover of which is denoted 100 by the reference numeral 21. The plate forming the lower surface 22 of the channel rests at one end on the upper flight 23 of an endless band 24 serving to feed forward the cigarettes while its other end is formed as 105 a rake, the prongs of which project into the semi-cylindrical grooves in the drum 4, these grooves being so deep that the prongs pass beneath the cigarettes in the pockets as shown particularly in Fig. 3^a.

The cigarettes are pushed forwards in the channel 21, 22 by following cigarettes delivered from the drum till they pass on to the upper flight 23 of the endless band 24 which is guided over the pulleys 25, 26. The pulley 25 is driven by chain 27 from the drum shaft 7. The upper flight of the endless band 24 which is narrower than the length of the cigarettes is led over a table 28. The cigarettes lying on this flight of the belt pass first beneath a fixed covering plate 29 against which the covering plate 30 abuts. This covering plate 30 forms one of the four arms of a star shaped rotating cross 34 which is rotatably mounted by means of a bush 33 on a vertical spindle 31 which is carried by the bracket arm 32. A spring coiled around the spindle 31 presses the bush 33 continuously downwards against the head 34 of the spindle 31 thereby holding the rotating cross in any given position. At the end of the feed band formed by the endless band 24 is provided a projection 35 against which the cigarettes are piled as they arrive. If these cigarettes, as is assumed in the example illustrated, are of oval cross-section, the distance of the covering plates 29 and 30 from the upper flight of the endless band 24 may be so dimensioned as to allow with the aid of the projection 35 the overlapping of the cigarettes which as is known is desirable in packeting oval cigarettes.

As shown in Figs. 1 and 2, three feeding devices for feeding the cigarettes to the main feed band are provided. As shown in Fig. 2 the endless bands 24 or their upper flights are arranged in steps in such manner that the one at the left hand side is highest while the two succeeding bands are each located at levels which are lower by the thickness of a cigarette. Between the separate feed bands 24 is located a portion 36' of a trough shaped guide 36 into which the cigarettes are fed while lying in their longitudinal direction to the slide Z. The portions of guide 36 are as regards height arranged to suit the height of the corresponding flights of the endless belt 34 i. e., they are also arranged in steps differing by the thickness of a cigarette.

The cigarettes are fed in the longitudinal direction of the guide 36 by pushers or plungers 37 which are secured to an endless chain 38 which at one end of the machine runs over the sprocket 39. Two parallel chains are provided (see Fig. 1) which carry cross members 40 from which controls project downwardly said pushers 37.

The pusher first strikes against the group of cigarettes which has been fed from the first feed band (i. e., that at the extreme right looking at Fig. 1) to the main guide. The cigarettes of this group are located

within the range of the covering plate 30 opposite the covering plate 29. The pusher comes against the ends of the cigarettes located between the upper flight of the endless band 24 and the covering plate 30 (it is assumed in the example illustrated that a group consists of 5 cigarettes). The cigarettes are carried forward by the pusher as the chain 38 carrying it moves in the direction of the arrow, Fig. 2. In order that the further supply of cigarettes to the pusher track should be interrupted during the time when the pusher is moving the group of cigarettes away from the transverse feed band a member 41 shown in detail in Figs. 6 and 7 is provided. This member is a two part presser so arranged that the two presser feet 42, 43 are carried by one bar 44 which is secured at the end of a double armed lever 45. The presser feet 42 and 43 hold between them the upper part of the endless band 24 which as already mentioned is narrower than the length of the cigarettes. The free end of the lever 45 bears with its roller 46 on the cam disc 47 which is mounted on the driven shaft 48 which is driven from the shaft 11 through worm gearing. On outward movement the pressers 42, 43 move into the path of the cigarettes which are located directly at the end of the cover plate 29 just where this plate abuts against the plate 30. The pressers 42, 43 as shown in Figs. 6 and 7 press the next succeeding cigarettes to be ejected softly against the fixed cover plate 29. As a result, during the time the pusher 37 feeds forward the five cigarettes into the path of the plate 30 the supply of further cigarettes into the path of the pusher cannot take place. The cigarettes held by the pressers against the fixed cover plate 29 form as it were a stop. As soon as the pusher has removed the five cigarettes the lever 45 swings back so that fresh cigarettes can be fed into the path of the pusher and to the projection 35.

On the ejection of the five cigarettes the pusher abuts against the plate 30 and moves said plate since the latter forms an arm of the rotating cross. In the further movement of the pusher the rotating cross is actuated in such manner that after completion of the movement of the pusher another arm 30 serving as a cover plate moves into the path of the projection 35 or of the endless band 24 or on the transverse feed band for the cigarettes. The pusher pushes the cigarettes on the portion 36' of the carrier 36 and then over the next group of cigarettes which have been fed from the second transverse feed band, the arrangement of this second feed band being the same as the first except that the corresponding endless band lies at a level lower by the thickness of

a cigarette than the first endless band 24. In consequence the cigarettes newly pushed forward lie above the cover plate 30.

The pusher is now lowered into the dotted 5 line position in Fig. 2 this movement of the pusher being effected by passing the lower flight of the endless chain 38 between a pair of sprockets 49, 50 which in conjunction with a further pair of sprockets 51, 52 serve 10 to lower this flight to the necessary extent.

The pusher 37 is thus lowered in such manner that it now feeds the two superposed groups of cigarettes on to the neighboring portion 36² of the main guide 36. At the 15 end of this portion two groups of cigarettes pass on to the cover plate 30 of the third feed band. The pusher is now again lowered so that it can grip the three groups of cigarettes and it feeds them on the guide 36 20 to the point where they are delivered to the shell slide Z. In case, due to any disturbance in the hopper 1 a pocket 5 of the drum 4 does not collect a cigarette so that the cigarettes are not fed forward quickly 25 enough by the cross feed bands and thus at the moment when the pusher is to move the cigarettes onto the guide 36 either there are no cigarettes to move or there are insufficient cigarettes, a safety device is provided.

30 This safety device has for its object to ensure that the number of cigarettes to be packed is always correct. There is provided for this purpose at the end of a lever 53 a feeler 54 adapted to project through 35 an opening in the stationary cover plate 29. The lever 53 is operated by a cam disc 55 on the shaft 48, the arm 53' of the double armed lever 53 bearing with its roller 56 against the periphery of the cam disc 55.

40 At the correct moment the lever 53 is swung outwards and the feeler 54 projects into the opening in the cover plate 29. The feeler 54 is mounted at the end of a rod 57 which is longitudinally movable in the eye 58 on

45 the end of the lever 53. About this rod is coiled a spring 59 which tends to press the feeler continuously downward. When the feeler in projecting inwards meets cigarettes it abuts against these cigarettes and on 50 downward movement of the lever 53 the rod 57 is moved longitudinally in the eye 58, the spring 59 being compressed. At the end of this rod is mounted a contact 61 carried by a blade spring 60 and adapted

55 to co-operate with the contact 62 secured on the machine frame. As shown in Fig. 4, when the cigarettes are in the guide the contact 61 cannot come in contact with the contact 62. If, however, there are no 60 cigarettes under the feeler 54 as in Fig. 5 then the feeler moves inwards the spring 59

remains expanded and the contact 61 comes in contact with a contact 62. The electric circuit thereby closed is used to accelerate 65 the drive of the feed drum 4 and the feed

drum is driven for a time at an increased speed and accordingly delivers more cigarettes. This operation continues as long as the cam portion of the cam disc 55 acts on the lever 53. The arrangement, may, however, be such that the increased speed of feed is only initiated by the closure of the circuit and the subsequent interruption of the circuit need not lead to reduction of the increased speed. 75

I claim:—

1. In a machine for assembling cigarettes, parallel feeders, guide members between said feeders arranged in stepped relation to one another and extending transversely to said feeders and longitudinally of the cigarettes, stepped abutments, pushers movable longitudinally on said guides so that when passing over the stepped guides they will be correspondingly lowered and discharge a group 80 of cigarettes from the guide of a higher level past the abutment on to the neighboring guide of a lower level and superpose a group of cigarettes on the latter, then push said superposed groups of cigarettes to a still 85 lower level and so on.

2. In a machine as per claim 1, in which the guides extending transversely to said feeders are stepped at levels varying from one another by the thickness of a cigarette. 95

3. In a machine as per claim 1, in which the pushers are carried by a parallel pair of flexible conveyors moving longitudinally of said guide, said conveyors having means for successively lowering said pushers to correspond with the different levels of said guide. 100

4. In a machine as per claim 1, in which near the forward end of each feeder are arranged in longitudinal extension of one another a fixed covering and a movable covering, said coverings forming with the corresponding feeder, a guide channel for a group of cigarettes, and a stationary abutment at said end of each feeder. 105

5. In a machine as per claim 1, in which near the forward end of each feeder are arranged in longitudinal extension of one another a fixed covering and a movable covering, said coverings forming with the corresponding feeder a guide channel for a group 110 of cigarettes, said movable covering being in form of a rotatable multiple armed member having means tending to securely hold said member in a position in which one arm at a time will form said movable covering. 115

6. In a machine as per claim 1, means for temporarily stopping the feeding of cigarettes at the time a group thereof is being advanced from each feeder on to the adjacent guide. 120

7. In a machine as per claim 1, means for temporarily stopping the feeding of cigarettes at the time a group thereof is being advanced from each feeder onto the adjacent guide, which said means include movable 125

presser feet adapted to engage and arrest the cigarettes located at the end of said fixed covering and in front of said movable covering.

5. In a machine as per claim 1, and in which near each feeder are arranged a fixed covering and a movable covering, said coverings forming with the corresponding feeder a guide channel for a group of cigarettes,

means for temporarily stopping the feeding of cigarettes including movable presser feet, a common swinging arm carrying said presser feet, said presser feet being spaced apart a distance less than the length of a cigarette so as to engage and press the same against said fixed covering. 10
15

In testimony whereof I affix my signature.
ROBERT WILHELM VOIGT.
